UNITED STATES PATENT OFFICE.

JULIAN OSTACHOWSKI, OF BUFFALO, NEW YORK.

MAIL-BOX.

1,140,914.

Specification of Letters Patent. Patented May 25, 1915.

Application filed October 19, 1914. Serial No. 867,851.

To all whom it may concern:

Be it known that I, JULIAN OSTACHOWSKI, subject of the Emperor of Austria - Hungary, residing at Buffalo, in the county of Erie and State of New York, have invented 5 certain new and useful Improvements in Mail-Boxes, of which the following is a specification.

This invention relates to certain new and 10 useful improvements in mail boxes.

The primary object of the invention is to provide a mail box in which the mail matter may be inserted when desired but is rendered incapable of being removed by any un- 15 authorized person.

A further object is to provide a combined mail feeder and slot guard occupying the upper portion of the mail box inwardly of the mail entrance slot and whereby the mail 20 is fed in small quantities from the slot to the mail receptacle and any returning of the mail from the receptacle to the slot is rendered impossible.

With these general objects in view and 25 others that will appear as the nature of the invention is better understood, the same consists in the novel combination and arrangement of parts to be hereinafter more fully described, illustrated in the accompanying 30 drawings and set forth in the appended claims.

In the drawings forming a part of this application and in which like-designating characters refer to corresponding parts 35 throughout the several views, Figure 1 is a front elevation of the device with a portion of the casing broken away, a portion thereof and of the revolute guard being shown in vertical section. Fig. 2 is an end elevation 40 of the device partially shown in central vertical section. Fig. 3 is a transverse vertical sectional view through the device adjacent one end thereof. Fig. 4 is a similar view taken upon a plane adjacent the other end 45 of the device, the same however being shown partially in elevation, and Fig. 5 is a horizontal sectional detail view of a portion of the device taken upon the line of the guard axle and of the actuator.

50 Referring more in detail to the drawings the mail box 10 is shown of substantially the usual external appearance having one curved or rear wall 11 and a mail entrance slot 12 provided in the forward wall which has a 55 hinged closure door 13 provided therefor.

A cylinder 14 is provided with a central

longitudinal axle 15 journaled in the opposite ends of the box and has opposite end disks 16 positioned adjacent the opposite end walls 17 of the box. The cylinder is 60 provided with longitudinally positioned non-radial blades 18 spaced apart and connecting the disks 16 and adapted to lie with the opening between the adjacent blades directly rearwardly and inwardly of the entrance slot 12 for allowing mail to be supported by the cylinder. One of the end disks 16 is provided on its outer face with radially arranged grooves or recesses 19 which are substantially V-shaped in form tapering 70 toward the axle 15 and decreasing in depth toward their pointed ends. A plunger 20 normally projected by the spring 21 is slidably mounted in a perforated boss 22 of the front wall of the casing and has an inner 75 hook 23 upon its inner end adapted to engage the recesses 19. The end wall 17 of the box is provided with a horizontally positioned guide member 24 having a slot 25 therein for accommodating the plunger 20 80 and directing its movement in a horizontal line. A ratchet wheel 26 having notches 27 is positioned upon the axle 15 adjacent the outer face of the opposite disk 16 and a pawl 28 is pivoted to the box end and is adapted 85 to enter the notches 27 of the ratchet wheel and is spring pressed by the leaf spring 29, secured to said end.

The complete operation of the device will 90 be apparent from the present detailed description thereof. The mail matter being placed through the entrance slot 12 is received on the cylinder 14 between the blades 18 and the disks 16 as best illustrated in Fig. 2 and thereupon the plunger 20 is forced 95 inwardly by the hand of the operator and moving in a horizontal line forces the hook 23 slidably against the rear wall of one of the recesses 19 which action thereby forces the cylinder to revolve a partial revolution, 100 being substantially a quarter turn whereupon the pawl 28 enters the succeeding one of the notches 27 which prevents any reverse rotation while the hook rides out of the engaged recess at the shallow pointed end 105 thereof and returns along the unbroken face of the disk under the action of the spring 21, the diameter of the perforation of the boss 22 being such as to allow sufficient play for this movement of the plunger. It will 110 be seen that the mail receiving cylinder may thus be revolved by the plunger 20 in a step-

by-step movement and as much as desired, while the mail matter is thus fed inwardly from the slot 12 to the mail receptacle portion 30 of the box upon a turning of the cylinder in the direction indicated by the arrow in Fig. 2. Any removal of the mail matter from the receptacle is completely prevented as the cylinder 14 entirely obstructs any outward movement of the mail matter to the slot 12, while the pawl and ratchet wheel prevent any reversal of the revolutions of the cylinder. The receptacle however is provided with an exit door 31 in the usual manner.

15 While the forms of the invention herein shown and described are what are believed to be the preferred embodiments thereof, it is nevertheless to be understood that minor changes may be made therein without departing from the spirit and scope of the invention as set forth in the claims.

What I claim as new is:

1. A device of the class described, comprising a box having a mail entrance slot 25 adjacent the top thereof, a cylinder horizontally journaled for revolution within the said box, projecting end disks at the opposite ends of the cylinder slightly spaced from the end walls of the box, non-radial 30 blades projecting from the cylinder and connecting the disks thereof and forming pockets between the adjacent blades and disks, one of said disks having V-shaped radial recesses on its outer side decreasing in 35 depth toward their pointed ends, a plunger slidably mounted through the front wall of

the box and having a hooked inner end adapted to engage the said recesses, a horizontally positioned slotted guide carried by the box and having said plunger positioned 40 therein, and a pawl and ratchet means for said cylinder preventing rearward movement thereof.

2. A device of the class described, comprising a box having a mail entrance slot, a 45 cylindrical feeder horizontally journaled within the box, there being spaced recesses formed in one end wall of the feeder, a reciprocating plunger carrying a hook adapted to be received in said recesses, and means 50 for preventing retrograde movement of the feeder, said recesses being formed whereby the hook carried by the plunger may be readily disengaged from said recesses.

3. A device of the class described comprising a box having a mail entrance slot adjacent the upper end thereof, a cylindrical feeder horizontally journaled within the said box and having a mail receiving pocket formed therein, spaced recesses having inclined bottom walls formed in one end wall of said feeder, a reciprocating plunger operatively received in said recesses, and pawl and ratchet stop means at the opposite end 60 of the cylinder from the said plunger to prevent retrograde movement of the feeder.

In testimony whereof I affix my signature in presence of two witnesses.

JULIAN OSTACHOWSKI.

Witnesses:

ANDRZEJ GELANSKI,

JOSEF KAWKA.
